UNITED STATES PATENT OFFICE.

ELLSWORTH R. BATHRICK, OF AKRON, OHIO.

EXERCISING APPARATUS.

1,142,137.

Specification of Letters Patent.

Patented June 8, 1915.

Application filed July 9, 1914. Serial No. 849,950.

To all whom it may concern:

Be it known that I, ELLSWORTH R. BATHRICK, a citizen of the United States, and residing at Akron, in the county of Summit and State of Ohio, have invented certain new and useful Improvements in Exercising Apparatus, of which the following is a specification.

This invention relates to exercising apparatus, and its primary object is to provide apparatus of this character in connection with a bed, the same constituting a permanent part of the bed structure.

The invention more particularly relates to horizontal bars adapted for exercising purposes which are supported by and serve as a permanent connection for the head and foot of a bedstead.

A further object of the invention is to provide novel means for bracing the head and foot of a bed to the side rails thereof, said bracing means also serving to support and rigidly brace the exercising bars above referred to.

One embodiment of the invention is illustrated in the accompanying drawing and its construction will be fully described herein-after in connection with the drawing which forms a part of this specification, and in which:—

Figure 1 is a view in perspective of a bed constructed in accordance with my invention and embodying a pair of horizontal bars, and other exercising devices. Fig. 2 is a detail sectional view of the horizontal-bar supporting means. Fig. 3 is a horizontal section on an enlarged scale of the wrist-exercising device shown in Fig. 1, and, Fig. 4 is a detail vertical section of the bracing means employed.

The reference numerals 1 and 2 designate the parallel side rails of the bed constructed of metal and connected in the usual manner to the head 3 and foot 4 of the bed. The head 3 comprises a transverse bar 5 and two oppositely-curved side supports 6 connected to the transverse bar 5 by parallel vertical bars 7 formed at their upper ends with sleeves 8 through which the curved side supports 6 extend and at their lower ends with horizontal sleeves 9 through which the transverse bar 5 extends. It will thus be seen that the inner member of each of the pairs of vertical bars 7 of the head of the bed are separated, permitting access to the bed between said bars.

The curved side supports 6 are connected at points opposite the ends of the side rails 2 by a truss rod 10 provided with sleeves 11 to receive the side supports 6 and the sleeves 12 having upwardly projecting sockets 13 to receive the lower ends of inclined braces 14, the upper ends of which are secured in sockets 15 depending from sleeves 16.

Between each pair of vertical bars 7 is supported a wrist exerciser of the construction shown in Fig. 3 and comprising a hollow spool 17 through which extends a bolt 18, the ends of which are secured to the bar 7 as shown in Fig. 3. Within the hollow spool is disposed a spiral spring 19, one end of which is secured to the spool and the other to one of the vertical bars 7, thus adapting the spool to be turned for wrist exercising. The foot of the bed comprises a horizontal bar 20 and two oppositely-curved side supports 21 and 22, the latter being connected by a truss 23. The truss 23 is secured to the upper ends of the curved side supports 21 and 22 by inclined braces 24 and vertical braces 24^a, the upper ends of which are secured in sockets 25 and 25^a depending from sleeves 26, said sleeves 26 being also formed with integral sockets 27 for the reception of the upper ends of the side supports of the foot of the bed.

The sleeves 16 and 26 are horizontally aligned for the reception of a pair of horizontal bars 28, and it will be noted that by this construction, the horizontal bars are supported at the upper ends of the vertical supports of both the head and foot of the bed, said vertical supports being separated as shown to permit free access to the bed from either end thereof to permit free access to the horizontal bars. The numeral 29 designates hand grasps depending from rings 30 which are freely slidable along the bars 28 and afford a means for arm exercise.

The side rails 1 and 2 are preferably braced to the ends of the bed by inclined braces 31 bolted or otherwise secured to the ends of the bed and to said side rails.

An important feature of the present invention is the manner of connecting and bracing the side rails to the ends of the bed by the truss braces shown, which afford a very rigid structure and firmly support the head and foot members of the bed to the side rails and also provide a substantial support for the vertical braces which support the horizontal exercising bars. A feature

of importance also is the means for securing the vertical supports of the two ends of the bed to the horizontal exercising bars 28, such means comprising the sleeves 16 and 26, 5 each formed with a depending lug 26^a and a coupling device comprising a plurality of sockets to receive the ends of the side supports and the upper ends of the vertical supports of the ends of the bed and also formed 10 with a socket 26^b on its upper side to receive the depending lugs 26^a of the sleeves 26 and 16.

In Fig. 4 I have illustrated a means for bracing the curved side members 21 and 22 15 of the foot of the bed to the vertical supports 24^a comprising tubular braces 32 secured by bolts 33 extending through the adjacent parts of the structure and into the ends of said tubular braces. The specific 20 relative arrangement and construction of these braces is not essential to the invention and may be varied indefinitely.

The depending lugs 26^a of the sleeves 26 are secured within sockets 26^b by cotter pins 34 and by merely removing the pins 34, the 25 horizontal bars 28 may be disconnected and removed from the bed when desired.

It will be noted that the construction as 30 above described permits access to the horizontal bars from either end of the bed and the said bars are firmly supported and constitute a part of the bed structure, serving as they do to connect the head and foot members together permanently.

35 While I have herein shown and described the preferred embodiment of the invention, I do not wish to confine myself thereto as various forms, modifications and arrangement of the parts as shown may be made 40 without departing from the spirit and scope of the invention as claimed.

What I claim as new is:—

1. The combination with the head and

foot members of a bed structure, of a pair of horizontal bars connecting said members, 45 horizontally-disposed truss braces connecting the sides of said members and vertical supports between said truss braces and bars.

2. The combination with the head and 50 foot members of a bed structure, each comprising separated side supports to permit access to the body from either end thereof, of a pair of horizontal exercising bars supported upon said side supports and connecting said head and foot members. 55

3. The combination with the head and foot members of a bed structure, of a pair of horizontal exercising bars supported upon said members, and means for supporting said bars comprising horizontally-aligned 60 sleeves provided with depending lugs, and sockets secured to said members adapted to receive said lugs.

4. The combination with the head and 65 foot members of a bed structure, each comprising separated side supports to permit access to the bed from either end thereof, of a pair of horizontal exercising bars supported upon said side supports and connecting said head and foot members, truss rods 70 connecting said side supports, vertical supports for said head and foot members, and means for connecting and supporting said horizontal bars and said side supports, each comprising a coupling device consisting of 75 a plurality of integral sockets to receive the ends of said side supports and vertical supports, an upper socket, and sleeve members each having a depending lug fitting within 80 said upper socket.

In testimony whereof I affix my signature in presence of two witnesses.

ELLSWORTH R. BATHRICK.
